TREATMENT OF HYDROCARBONS

Valentine Mekler, Jackson Heights, N. Y., assignor to The Lumus Company, New York, N. Y., a corporation of Delaware

Application February 20, 1943, Serial No. 476,563

3 Claims. (Cl. 260—673.5)

This invention relates to the treatment of hydrocarbons and particularly to a process of converting hydrocarbons in the vapor phase whereby a high yield of high-octane motor fuel is obtained. More specifically, this invention relates to a multistage process for converting relatively heavy predominantly paraffinic hydrocarbons into lighter predominantly aromatic hydrocarbons, in which process a combination of thermal and catalytic cracking, cyclizing and dehydrogenating operations is so utilized that the paraffinic hydrocarbons are selectively and progressively converted into aromatic hydrocarbons suitable for use in a high-octane motor fuel. This application is a continuation in part of my prior co-pending application, Serial No. 280,961, filed June 24, 1939.

It is well known to the art to convert heavy hydrocarbons into gasoline-like hydrocarbons in the vapor phase under suitable conditions of temperature and pressure, either with or without the use of catalysts. It is customary to pass the hydrocarbon vapors through a conversion unit, in which they are subjected to one set of conversion conditions of temperature, pressure, and time of contact. As a result, only certain constituents of the complex hydrocarbon mixture undergo favorable reactions, the remainder of the hydrocarbons either being overconverted or remaining unchanged, with a resultant loss in the yield and the quality of the final product. In addition, uncondensable gas and carbon may be formed in such quantities as to adversely affect the ultimate yield of the finished product.

It is also well known that each particular hydrocarbon has its own specific optimum conversion conditions and that the maximum yield of desirable converted product is not obtained if the hydrocarbon is not subjected to these conditions. Further, it is known that, for paraffinic hydrocarbons, the optimum temperature for cracking decreases with an increase in the molecular weight of the hydrocarbons treated. For instance, it has been determined that the approximate decomposition temperature for ethane is 1550° F. and that for hexadecane at the same pressure is about 875—930° F. In addition, it has been found that the stability of hydrocarbons of the same molecular weight at cracking temperatures increases from paraffins to aromatics as follows: paraffins, olefines, diolefines, naphthenes, and aromatics.

It is the principal object of my invention to subject relatively heavy paraffinic hydrocarbons

to a multistage conversion process, in which the hydrocarbons are selectively and progressively converted into aromatic hydrocarbons of high octane rating.

5 Another object of my invention is to effect a selective conversion of relatively heavy paraffinic hydrocarbons by passage of such hydrocarbons through a series of conversion stages, each stage being comprised of a heating unit and a catalytic conversion unit, the heating unit serving primarily to heat the vapors of the hydrocarbons to a predetermined temperature suitable for the selective conversion of a particular group of the hydrocarbons in the accompanying catalytic unit, 10 the catalytic conversion unit being maintained at the predetermined temperature for the conversion. Although the heating unit serves primarily to raise the temperature of the hydrocarbon vapors undergoing treatment, it will be understood that some cracking of the hydrocarbons may also take place therein.

15 A further object of my invention is to control the conversion conditions in the catalytic units throughout the process so that the predominant reaction in the first stages is the selective conversion of the heavier paraffins into olefines and lighter paraffins, in the intermediate stages the selective conversion of the lighter paraffins into olefines and of the olefines into alicyclic compounds such as cyclo-olefines, and in the latter stages the selective conversion of any remaining olefines into alicyclic compounds and of the alicyclic compounds into aromatics.

20 25 30 35 Further objects and advantages of my invention will be apparent from the following description of a preferred form of embodiment thereof taken in connection with the attached drawing, illustrative thereof, such drawing being a flow sheet in accordance with a preferred form of embodiment of the invention.

35 40 45 50 In accordance with the present invention, the relatively heavy paraffinic hydrocarbons are first vaporized, and all the vapors are then passed through a series of conversion stages, each comprised of a heating unit and a catalytic unit and each maintained at a predetermined temperature which is favorable for the selective conversion of a particular group of such hydrocarbons. Accordingly, the hydrocarbons which are converted under the mildest conditions are acted upon first, and then those hydrocarbons more difficult to convert are successively acted upon by reason of the gradual increase in the severity of the conditions to which the hydrocarbons are subjected.

Each stage also prepares the hydrocarbons for treatment in the succeeding stages. For instance, in the first stages the heavier paraffinic hydrocarbons are thermally and catalytically converted into olefines and lighter paraffins, which then are further treated in the following stages, the olefines being cyclized into cyclo-olefines, the cyclo-olefines being dehydrogenated into aromatics, and the lighter paraffins being additionally converted into olefines. Furthermore, this process has a sufficient flexibility so that the operating conditions may be readily and easily changed to take care of a wide range of starting stocks and to provide a variety of end products.

Although any number of stages, which may be necessary to effect the desired conversion, may be used, the invention will be described as embodied in a three-stage system, in which the first stage serves to convert the heavier paraffins into olefines and lighter paraffins, the second stage serves to convert the lighter paraffins into additional olefines and the olefines into alicyclic compounds such as cyclo-olefines, and the third stage serves to convert the remaining olefines into cyclo-olefines and the cyclo-olefines into aromatics.

In accordance with a preferred form of embodiment of my invention, a crude oil is charged to fractionating tower 10 at 12 after it has been suitably preheated in heater 14. Tower 10 may be of any conventional type of fractionating apparatus such as a bubble plate tower suitable for separating the crude oil into a plurality of fractions. An overhead fraction is taken off at 16 and is condensed at 18, part of the condensate being returned as reflux at 20 and the remainder being removed at 22 as straight-run gasoline. Side streams such as naphtha, kerosene, light gas oil, and heavy gas oil are removed at 24, 25, 26, and 27, respectively. A bottoms stream is removed from the tower at 28.

Each of the above side streams may be subjected to my multistage conversion process if desired. For convenience, however, my invention will be described in connection with the treatment of the light gas oil side stream, it being understood that the invention is equally applicable to the treatment of any or all of the other side streams.

The light gas oil side stream, which is removed at 26, is passed by pump 26a to a multistage conversion system indicated generally at 29, 30, and 31. Each of these stages consists of a heating coil indicated at 32, 33, and 34 and a vapor-phase catalytic conversion unit indicated at 35, 36 and 37.

In coil 32 the gas oil side stream is vaporized and heated to the temperature of conversion necessary in catalytic chamber 35 to most favorably convert the heavier paraffinic fractions thereof. Incipient cracking of the heavy hydrocarbons may occur during passage through coil 32, but conditions are controlled to prevent undesirable side reactions from taking place. Catalyst chamber 35 may be of a type in which the catalyst is maintained in situ, but a catalyst chamber in which both vapors and catalyst flow through in continuous streams is preferred.

In the catalyst chamber 35 (conventionally shown), the vapors entering at 38, preferably flow upwardly countercurrently to the catalyst, which is moved downwardly through the chamber in a continuous stream by suitable means (not shown). The catalyst, which may be of

any type suitable for effecting the desired conversion, is fed to the chamber at 39 and is withdrawn at 40. The spent catalyst may be reactivated or thrown away as desired. The vapors which leave catalyst chamber 35 near the top consist primarily of olefines and light paraffins. Preferably, the catalyst chamber is equipped with heating means (not shown) so that the temperature of the vapors passing therethrough is maintained at the proper level.

The partially converted vapors from chamber 35 are passed through coil 33, in which they are heated to a temperature normally higher than that maintained in the previous stage, which is suitable for the conversion in catalyst chamber 36 of the light paraffins into olefines and the cyclization of the olefines into alicyclic compounds such as cyclo-olefines. Cracking of the hydrocarbons may also occur in coil 33, but again undesirable side reactions are held to a minimum. The vapors leaving coil 33 may pass directly to catalyst chamber 36 in line 41, or they may be diverted in whole or in part through line 42 to tar separator 43, where any tar inadvertently formed in previous operations may be knocked out and removed at 44. From the tar separator the vapors pass to chamber 36 through line 41. Catalyst chamber 36 is similar in operation to chamber 35; hydrocarbon vapors enter at 45, flowing countercurrently to the catalyst, which is fed in at 46 and withdrawn at 47. The vapors leaving chamber 36 at 48 are composed mainly of olefines and cyclo-olefines and may contain unconverted light paraffins.

These vapors are then passed to the third conversion stage, in which they are heated in coil 34 preferably to a higher temperature than that maintained in stage 36 before they are introduced into catalyst chamber 37 at 53. Tar separator 50 may also be provided for removal of tar at 51.

In this last stage the hydrocarbons are preferably heated to a temperature sufficient to convert into olefines any light paraffins which may have been unconverted in the previous stages. Usually this temperature is so high that the vapors cannot be subjected to the action of the cyclizing and dehydrogenating catalyst in chamber 37 without deleterious effect on the catalyst. In this case the vapors issuing from coil 34 are cooled in cooler 51a to a temperature such that the catalyst is not adversely affected. Catalyst chamber 37 is also preferably operated in the same manner as the other catalyst chambers with the catalyst fed in at 55 and removed at 56.

The conversion products leaving the final conversion stage are passed to fractionating tower 58, also preferably a bubble plate tower, in which the vapors are fractionated into a high-octane gasoline, removed as overhead at 60, and a bottoms, withdrawn at 62. The overhead is condensed at 63, reflux is returned to the tower at 64, and high-octane gasoline is withdrawn at 65. This high-octane gasoline may be subjected to any desired stabilizing and refining operations which may be necessary to obtain a specific finished product. The bottoms withdrawn at 62 may be recycled as by means of line 74 for admixture with the charge to pump 26a. If the bottoms has such a composition that recycling cannot be carried out, it may be withdrawn at 76 and treated in any desired fashion, or it may be removed to storage.

If desired, conversion products from other

multistage conversion systems may be commingled with the vapors flowing in line 68 as at 70 and 71, and the mixture passed to tower 58 at 72.

Although provision is made at 43 and 50 for the removal of any tar previously formed, it will be clear from the description and the drawing that substantially the entire hydrocarbon charge is subjected to each stage of the conversion system. Furthermore, with the type of catalyst chamber described, it may be found that separators 43 and 50 are not needed since any tar formation will be deposited on the catalyst and continuously removed.

Conversion conditions differ in each stage so that optimum conversion of the hydrocarbon charge may be effected. The degree of heating to which the hydrocarbon vapors are subjected varies from stage to stage as well as the temperature, the time of contact, and the catalyst in the catalytic unit. In addition, for charging stocks of different types, these conditions also vary.

In the form of embodiment described, in the first stage the main object is to convert the heavier paraffin hydrocarbons into olefines and lighter paraffins. For this purpose, a catalyst suitable for splitting heavy hydrocarbons is used. Such catalyst may be selected from the oxides of aluminum, nickel, cobalt, molybdenum, and chromium, for example, and may be in admixture with silica gel, activated alumina, pumice, and the like; or it may comprise any other substance suitable for effecting a splitting reaction of the type desired. The temperature in this stage may range from 600 to 750° F.

The second stage has for its main object the conversion of the lighter paraffins not affected in the first stage into olefines and the cyclization of the olefines into alicyclic compounds such as cyclo-olefines. Although a catalyst similar to the one used in the first stage may be employed in the second, the temperature level is higher, ranging from 750 to 950° F., and the contact time is lower.

In the third stage, the main object is the cyclization of the remaining olefines into cyclo-olefines and the dehydrogenation of the cyclo-olefines formed in the previous stage into aromatic hydrocarbons. The catalyst employed may be one of the metallic oxides which are suitable for effecting the cyclization of olefines into cyclo-olefines and the subsequent dehydrogenation thereof into aromatics. For such purpose, chromium oxide, preferably specially prepared so as to increase its activity, may be used; desirably, however, this oxide is used in admixture with other catalytic materials such as alumina, nickel, and oxides of such metals as iron, molybdenum, tin, tungsten, and vanadium. Other oxides such as zinc oxide are also suitable. Heavy metal salts may also be used as the catalyst; among these may be mentioned the molybdates and tungstates of nickel, vanadium, chromium, iron, and titanium, as well as other salts including chromates such as zinc chromate and sulfides such as zinc sulfide. The temperature in the heating coil ranges from 950 to 1350° F., but a temperature somewhat lower, within the range of 900 to 1000° F., is maintained in the catalyst chamber so that the catalyst is not subjected to too high temperatures.

Although in each stage of this selective conversion process, reactions of cracking, cyclization, dehydrogenation, polymerization, and the

like are taking place to some extent simultaneously, the predominant reaction in each stage is so controlled by the temperature, contact time, and catalyst used that undesirable side reactions are held to a minimum. By means of this control over temperature, contact time, and catalyst, in each stage a desired selective conversion of the hydrocarbons undergoing treatment takes place. In each stage the reactions are controlled so that stable intermediate hydrocarbons are formed; and, by means of the heating step, the hydrocarbons are prepared for the next step of selective catalytic conversion. Although thermal cracking does occur to some extent in the various heating coils, the conversion is accomplished principally by catalytic action.

Since the main part of the conversion reactions is catalytic in nature, high pressures are not necessary to carry on the operation of the process. Pressures only slightly above atmospheric need be employed, the pressure being at least sufficient to overcome the pressure drop through the apparatus. The yield of gasoline hydrocarbons, however, is higher than that of single-stage catalytic conversion processes, and the end point of the product obtained is also under substantially better control.

The problem of catalyst reactivation is taken care of outside of the system since spent catalyst is continuously removed from the bottom of the catalyst chambers while fresh catalyst is supplied at the top thereof. Any carbon or tarry material that deposits on the catalyst does not effectively alter the activity of the catalyst with respect to the particular reaction since the catalyst is continuously withdrawn from the chambers. Similarly, sulfur poisoning does not affect the catalyst activity to an appreciable extent.

While I have described a preferred form of embodiment of my process, I am aware that there may be modifications thereto; and I, therefore, desire a broad interpretation of my invention within the spirit and scope of the description herein and of the claims appended hereinafter.

I claim:

1. The process of converting relatively heavy predominantly paraffinic hydrocarbons into relatively light predominantly aromatic high-octane gasoline hydrocarbons, which comprises vaporizing the paraffinic hydrocarbons and heating the resulting vapors to a temperature of 600 to 750° F., passing the heated vapors into contact with a catalyst selected from the group consisting of the oxides of aluminum, silicon, nickel, cobalt, molybdenum, and chromium primarily to crack the heavier paraffinic hydrocarbons into olefinic hydrocarbons and lighter paraffinic hydrocarbons, heating the partially converted vapors to a temperature of 750 to 950° F., passing the heated vapors into contact with a catalyst selected from the group consisting of the oxides of aluminum, silicon, nickel, cobalt, molybdenum, and chromium primarily to crack the lighter paraffinic hydrocarbons into olefinic hydrocarbons and to partially cyclize the olefinic hydrocarbons into cyclic hydrocarbons, the time of contact of the vapors with the catalyst in this second cracking stage being less than that in the first cracking stage, then further heating the vapors to a temperature of 900 to 1000° F., passing the heated vapors into contact with a catalyst capable of cyclizing olefinic hydrocarbons into cyclic hydrocarbons and dehydrogenating cyclic hydrocarbons into aromatic hydrocarbons pri-

marily to cyclize the remaining olefinic hydrocarbons into cyclic hydrocarbons and to dehydrogenate the cyclic hydrocarbons into aromatic hydrocarbons, and fractionating the converted vapors to obtain the desired high-octane aromatic gasoline fraction.

2. The process of converting relatively heavy predominantly paraffinic hydrocarbons into relatively light predominantly aromatic high-octane gasoline hydrocarbons, which comprises vaporizing the paraffinic hydrocarbons and heating the resulting vapors to a temperature of 600 to 750° F., passing the heated vapors into contact with a catalyst selected from the group consisting of the oxides of aluminum, silicon, nickel, cobalt, molybdenum, and chromium primarily to crack the heavier paraffinic hydrocarbons into olefinic hydrocarbons and lighter paraffinic hydrocarbons, heating the partially converted vapors to a temperature of 750 to 950° F., passing the heated vapors into contact with a catalyst selected from the group consisting of the oxides of aluminum, silicon, nickel, cobalt, molybdenum, and chromium primarily to crack the lighter paraffinic hydrocarbons into olefinic hydro-

5
10
15

25

carbons and to partially cyclize the olefinic hydrocarbons into cyclic hydrocarbons, the time of contact of the vapors with the catalyst in this second cracking stage being less than that in the first cracking stage, then further heating the vapors to a temperature of 950 to 1350° F. to crack any remaining light paraffinic hydrocarbons into olefinic hydrocarbons, lowering the temperature of the vapors to about 900 to 1000° F., passing the vapors thus temperature-conditioned into contact with a catalyst capable of cyclizing olefinic hydrocarbons into cyclic hydrocarbons and dehydrogenating cyclic hydrocarbons into aromatic hydrocarbons primarily to cyclize the remaining olefinic hydrocarbons into cyclic hydrocarbons and to dehydrogenate the cyclic hydrocarbons into aromatic hydrocarbons, and fractionating the converted vapors to obtain the desired high-octane aromatic gasoline fraction.

3. The process as claimed in claim 2, in which the predominantly paraffinic hydrocarbons comprise a fraction boiling within the range of gas oil.

VALENTINE MEKLER.
